ELECTRIC CABLE

Charles E. Bennett, Ridgewood, N. J., assignor to
The Okonite-Callender Cable Company, Incorporated,
Paterson, N. J., a corporation of New Jersey

Application September 26, 1942, Serial No. 459,762

3 Claims. (Cl. 174—24)

1

This invention relates to an improvement in electric cables of the buoyant type, namely, cables which are adapted readily to float in sea water.

Among the objects of my invention is the provision of a buoyant cable which is rugged in construction so as readily to withstand the rough usage to which such cables are subjected, sufficiently flexible to permit the same to be handled and reeled without difficulty, and air cooled. By air cooling the cable I increase its current-carrying capacity, thereby permitting a reduction in conductor size for a given duty as compared with prior buoyant cables.

In addition to air cooling the cable I provide for maintaining the air employed at a substantial pressure, say, 100 to 150 pounds per square inch, so that should the cable be punctured below the water line, the water will be prevented from entering the cable, and the cable will remain afloat and usable until repairs can be effected.

More specifically my invention provides a construction wherein the cable is composed of a continuous hollow spiral core of metal, heavy cardboard, fibre or other suitable material, about which the cable conductors are laid. Air is introduced into this hollow core from an air compressor which is mounted on a ship to which the cable is attached when in use.

Still more specifically my improved cable comprises a hollow spiral core, such as above referred to, and extending the length of the cable. Stranded immediately about this hollow spiral core is one of the cable conductors. About this conductor I apply an insulating layer of rubber, natural or synthetic, or rubber-like material. Over this insulating layer I strand a second conductor about which in turn I apply an insulating layer similar to the first one mentioned. In addition to the construction so far referred to, my cable comprises a series of floats of wood, for instance, or other suitably buoyant material, these floats not only providing additional buoyancy for the cable but also protecting the cable against mechanical injury.

In the accompanying drawing wherein I have illustrated one embodiment of my invention:

Fig. 1 is a diagrammatic view showing my improved cable floating upon the water and attached to a ship; and

Fig. 2 is a sectional elevational view of a short length or piece of the cable illustrated diagrammatically in Fig. 1.

Referring to the drawing in detail: My improved cable comprises a tubular core member 2

which has been illustrated as a hollow spiral. This member may be composed of metal or treated paper or other suitable material and extends the length of the cable.

Stranded immediately about this tubular core member is cable conductor 4. 6 designates an insulating layer over the conductor 4. This layer is of rubber, natural or synthetic, or other suitable flexible rubber-like insulating material. 8 designates the second conductor of the cable which is stranded about the insulating layer 6, and in turn is covered with a sheath 10 of rubber, natural or synthetic, or other suitable rubber-like material.

15 Threaded or strung upon the layer 10 are a plurality of floats 12 of highly buoyant material, such, for example, as wood or wood pulp treated to render the same highly water-resistant. In order that the flexibility of 20 the cable will not be detrimentally impaired the floats 12 may be so shaped at their adjacent ends as in effect to provide a flexible joint or they may be spaced sufficiently far apart on the cable so as not to interfere with flexing of the cable when 25 the same is being handled or being reeled.

It will be understood of course that the weight to volume ratio of my improved cable is such as to render the cable buoyant in water.

When my improved cable is in operation, as 30 above indicated, I propose to maintain the tubular core 2 under substantial internal air pressure, so that in practice the inner end of the cable is attached to an air compressor, which I have indicated diagrammatically at 14, mounted on the ship 16 to which the end of the cable is attached. This air compressor is capable of maintaining an internal air pressure of say 100 to 150 pounds to the square inch throughout the length of the cable. One of the functions of this air is to cool 35 the cable conductors thereby increasing their current-carrying capacity for a given size conductor, or permitting of reduction in the conductor size for a given duty.

In my copending application Serial No. 449,574, 40 filed July 3, 1942, I have shown a cable of the buoyant type in which I employ water for the cooling medium. It will be appreciated that the present cable possesses certain advantages over my prior cable in that the pressure drop over a 45 long length of cable of the type of the present application is negligible, while owing to the fact that air is so much lighter than water a buoyant cable can be produced the overall dimensions of 50 which are much less than with the water cooled type.

As above mentioned, not only does the air function as a cooling medium but by maintaining the air at superatmospheric pressure, say 100 to 150 pounds per square inch, water is kept out of the cable, and should the cable be punctured, it will remain afloat and usable until repairs can be effected.

It is to be understood that changes may be made in the details of construction and arrangement of parts hereinabove described within the 10 purview of my invention.

What I claim is:

1. A flexible electric cable comprising in combination a hollow core, a conductor stranded about said core, a flexible insulating layer of rubber-like material about said conductor, a second conductor stranded about said insulating layer, a flexible insulating layer of water impermeable rubber-like material over said second conductor, floats strung upon said last mentioned insulating layer, and an air compressor for supplying air to the interior of said core in such volume as to maintain the core under superatmospheric internal pressure, the weight to volume ratio of the cable being such as to render the same buoyant 25 in water.

2. A flexible electric cable comprising in combination a tubular hollow core of flexible material wound in an open helix, a conductor stranded directly about said core, a flexible, electrically insulating, air and water impermeable sheath about said conductor, a second conductor stranded about said sheath, a flexible, electrically insulating, air and water impermeable sheath about said second conductor, floats strung upon the last mentioned sheath, the end of one float being convex and the adjacent end of the next float being concave to permit the floats to telescope each other without impairing the flexibility of the cable, and means to supply compressed air to the said cable core at sufficient pressure to maintain the first mentioned sheath under sufficiently high internal pressure as to prevent the entry of water to 40

the interior of the cable beneath the first mentioned sheath in the event of puncture of said sheath; the weight to volume ratio of the cable being such as to enable the same to float in water.

3. A flexible electric cable comprising in combination a tubular hollow core composed of paper tape wound in an open helix, a conductor stranded directly about said core, a flexible sheath of air and water impermeable material immediately about said conductor, a second conductor stranded about said sheath, a flexible sheath of air and water impermeable material immediately about said second conductor, wooden floats treated to increase their resistance to water strung upon 15 said second sheath, the adjacent ends of adjacent floats being shaped to provide for free flexing of the cable, and means for supplying air to the said core to maintain the first mentioned sheath under superatmospheric internal pressure to prevent the entry of water, in which the cable is floating, to the interior of the cable, beneath the first mentioned sheath, the weight to volume ratio of the cable being such as to enable the same to float in water.
